CROSSCUT SAW

Nicolai Nilsen, Wallace, and Thorvald R. Christofferson, Gem, Idaho

Application June 3, 1941, Serial No. 396,450

2 Claims. (Cl. 143—46)

The present invention relates to new and useful improvements in cross cut saws and has for one of its important objects to provide, in a manner as hereinafter set forth, a machine of this character comprising a power driven circular saw which is adapted to swing in a true horizontal plane.

Another very important object of the invention is to provide a cross cut saw machine of the aforementioned character comprising a novel construction and arrangement whereby substantially any desired adjustment of the saw may be expeditiously made for performing different kinds of work.

Other objects of the invention are to provide a cross cut saw machine of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a saw machine constructed in accordance with the present invention.

Figure 2 is a view in front elevation thereof.

Figure 3 is a top plan view.

Figure 4 is a view in front elevation of the post with the elements thereon.

Figure 5 is a vertical sectional view, taken substantially on the line 5—5 of Figure 4.

Figure 6 is a view in horizontal section, taken substantially on the line 6—6 of Figure 4.

Figure 7 is a detail view in perspective of the slide to which the guard leveling link is connected.

Figure 8 is a detail view in cross-section, taken substantially on the line 8—8 of Figure 3.

Referring now to the drawings in detail, it will be seen that the embodiment of the invention which has been illustrated comprises a post 1 which is rigidly secured in any suitable manner, as at 2, on the back of a table 3. Slidably and rotatably mounted on the upper end portion of the post 1 is an elongated, tubular metallic cap 4. Rotatably mounted in the closed upper end of the cap 4 is a vertical adjusting screw 5 which is threadedly engaged in a bore provided therefor in the upper end portion of the post 1. A suitable operating handle 6 is provided for the ad-

justing screw 5. The lower portion of the cap 4 is in the form of a vertically split clamp which is provided with suitable means 7 for frictionally securing said cap in adjusted position against 5 rotation on the post 1.

Fixed on the lower portion of the front of the sleeve 4, as at 8, and depending therefrom is a worm segment 9. Mounted on the lower portion of the segment 9 is a guide 10 which is slidable 10 on the post 1. Pivottally mounted on the lower portion of the stationary worm segment 9 is a swinging segment 10 of suitable metal. The upper portion of the swinging segment 10 is formed to provide a housing 11 of angular cross-section 15 in which the segment 9 is engaged. The housing 11 includes a raised portion 12 in which a worm gear 13 on one end portion of a hand actuated shaft 14 is journaled, said worm gear 13 being in mesh with and adapted to travel on the worm 20 segment 9 for swinging the pivoted segment 10 in a vertical plane from side to side.

Rigidly mounted on the swinging segment 10 and projecting horizontally therefrom is a substantially U-shaped frame 15 of angle iron. 25 Mounted on the free end portions of the legs of the U-shaped frame 15 are uprights 16 of suitable metal. The uprights 16 have formed therein at intermediate points vertical slots 17 which accommodate bolts 18 whereby said uprights are 30 secured for vertical adjustment on the frame 15. The uprights 16 are further provided, in their upper portions, with vertical slots 19 the purpose of which will be presently set forth.

Pivottally mounted on the lower end portions 35 of the uprights 16 for swinging movement in a vertical plane are links 20. The links 20 have one end portion pivotally secured to bosses or the like 21 (see Figures 2 and 3) which project from an intermediate portion of a beam 22. The upper end portion of the beam 22 is journaled on a rod 23 which has its end portions slidably secured in the slots 19 in the uprights 16. Rotatably mounted on the lower end portion of the beam 22 is a vertical circular saw 24.

45 As illustrated to advantage in Figure 8 of the drawings, an eccentric 25 is mounted for rotary adjustment on the rod 23 and secured by a set screw 26. Journaled on the eccentric 25 is a double pulley 27. An endless belt 28 drives the saw 50 24 from the pulley 27. By rotatably adjusting the eccentric 25 on the rod 23 the tension of the belt 28 may be regulated as desired.

Pivottally mounted for rocking adjustment on the frame 15 is a motor base 29. Mounted on the base 29 is a suitable electric motor 30. A belt 31

from the motor 30 drives the pulley 27. A coil spring 32 is connected to the swinging motor base 29 for maintaining the belt 31 at the desired tension at all times. It will thus be seen that the saw 24 is operatively connected to the electric motor 30.

Fixed on one end portion of the rod 23 is a bracket 33 which is slidable on the adjacent upright 16. The bracket 33 includes projections 34 (Fig. 7) which receive the adjacent uprights 16 therebetween for securing the rod 23 against rotation while permitting vertical movement thereof. Mounted for swinging adjustment on the lower end portion of the beam 22 is a hood or guard 35 for the saw 24. A link 36 has one end pivotally connected to the bracket 33 and its other end pivotally connected to the guard 35 for maintaining said guard in a horizontal position at all times as the saw is swung across the work on the table 3. A suitable handle 37 is provided on the front of the guard 35 for manipulating the saw 24.

Mounted on the frame 15 is a bracket 38. Pivotally mounted on the bracket 38 is a clamp 39 one end of which is engaged with the toothed stationary segment 9. Threadedly mounted in the other end portion of the clamp 39 is a hand screw 40 which is engaged with the frame 15 for actuating said clamp. The clamp 39 is adapted to engage the segment 9 for securing the frame 15 in adjusted position.

It is thought that the operation of the machine will be readily apparent from a consideration of the foregoing. Briefly, the electric motor 30 which, of course, may receive current from any suitable source, drives the saw 24 through the belt and pulley connections 31 and 28. The work is placed on the table 3 and the saw 24 is swung thereacross. The mounting of the beam 22 on the uprights 16 is such as to cause the saw 24 to travel in a true horizontal plane back and forth across the table. Through the medium of the worm 13 traveling on the segment 9 the frame 15 may be conveniently tilted for adjusting the saw 24 to any inclination. By rotating the entire assembly on the post 1 the saw 24 may be expeditiously positioned to move across the work at any desired angle. Then, the screw 5 facil-

tates vertical adjustment of the entire assembly on the post 1. From the foregoing it will be seen that the saw 24 is capable of substantially universal adjustment. Thus, various kinds of work may be rapidly and accurately performed. Further, a dado may, if desired, be substituted for the saw 24.

It is believed that the many advantages of a saw machine constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A saw machine of the character described including a post, a segmental gear mounted for vertical adjustment on said post, means for adjusting the gear, a member pivotally mounted for swinging adjustment on said gear, a frame fixed on said member, a circular saw mounted on said frame, means for actuating the saw, a manually operable worm gear rotatably mounted on the member and engaged with the first-named gear for adjusting said member, a bracket mounted on the frame, a clamp pivotally mounted on said bracket and engaged with the first-named gear, and a hand screw threadedly mounted on one end portion of the clamp and engaged with the frame, said screw constituting means for securing the clamp against the first-named gear.

2. A saw machine of the character described comprising a supporting structure including a pair of uprights having vertical slots therein, a rod mounted for vertical sliding movement in the slots, a bracket mounted on the rod and slidable on one of the uprights, a swinging beam mounted on the rod, a rotary saw mounted on said beam, means for actuating the saw, a guard for the saw rockably mounted on the beam, a link connecting the guard to the bracket for rocking said guard upon swinging movement of the beam, and a pair of links pivotally connected to the beam and the uprights.

NICOLAI NILSEN.

THORVALD R. CHRISTOFFERSON.
